KEROSENE

Joshua A. Tilton, Baton Rouge, La., assignor to
Standard-I. G. CompanyNo Drawing. Application August 1, 1936,
Serial No. 93,765

6 Claims. (Cl. 196—150)

This invention relates to improved burning oils and methods of producing same, and it relates more particularly to improving kerosene stocks which are normally of too low a quality to be used as burning oils.

It is well known in the art, that kerosenes containing appreciable quantities of either aromatic or unsaturated hydrocarbons or both give unsatisfactory performance when used as illuminants as is evidenced by smoking, fogging of chimney, streaking flames, soot formation, wick incrustations, clogging of wick, etc. The illuminating powers and burning characteristics of kerosenes are usually judged by the "paraffinic-ity" which is generally measured in terms of the density of the oil in relation to its viscosity. It is known that with wick fed lamps of normal design the viscosity of the kerosene in the reservoir should not exceed 450 Saybolt-thermo viscosity (New and Revised Tag Manual for Inspectors of Petroleum (1930) Test No. 6) or approximately 2 centipoises; but oils of Saybolt-thermo viscosities lower than 450 and around 325 to 375 are quite satisfactory. The lower the specific gravity (higher A. P. I. gravity) for kerosenes of similar viscosities the higher the paraffinic-ity and the better the quality. Generally the burning oils placed on the market are required to meet certain specifications as to gravity. For example, one large producer makes three grades of kerosenes of similar viscosities, having gravities A. P. I. of 41.0—44.0—and 46.0 minimum, respectively.

Inasmuch as the preparation or refinement necessary for the higher quality burning oils involves substantial expense, the difference in quality as expressed by A. P. I. gravity is generally reflected in a difference in market price as shown in the following table:

Table I

	A. P. I. gravity	Cost
		\$/gal.
47		5.50
46		5.375
45		5.250
42-44		4.375
41-43		4.125
38-40		3.00

Ultimately the quality of kerosenes as illuminants are best judged from performance in service; but there are arbitrary tests by which the quality may be predicted. The "smoke point", as described by Woodrow (Proceedings World Petroleum Congress 1933, Vol. II, 732), Kewley and

Jackson (J. I. P. T., 1927, 13,364), Minchen (J. I. P. T., 1931, 17, 103), and Gilbert (Proceedings World Petroleum Congress 1933, Vol. II, 735), is a satisfactory and simple test for measuring the relative quality of kerosenes. In this test the oil is burned in a Weber lamp and the flame height at the point at which a smoky flame is produced is determined as the "smoke point". The highest quality kerosenes produce the highest flame height before smoke appears. Examples of flame heights for different grades of kerosenes are as follows:

(1) Highest quality	29 to above 32
(2) Cheap quality	20 to 21.
(3) Inferior grade	12.5 15

Gilbert shows by a series of actual tests and calculations that the "smoke point" may be closely estimated for kerosenes by the use of the following formula:

$$S. P. = 32 - \frac{E}{2} + 100(d - 0.785)$$

where S. P.=Smoke point

E=Percentage extractable by 3 volumes of 98% sulfuric acid 25

d=Specific gravity after sulphonation

Although kerosenes of low "smoke point" may in certain cases be improved by certain treatments, such as by solvent extraction or by hydrogenation, these processes involve considerable expense and are practical only in certain cases where the paraffinic-ity or "smoke point" is not extremely low, or where the raw material has certain properties.

On the other hand, the present invention offers a very simple and economical method of improving the "smoke point" and other properties of any kerosene stock up to the desired specifications.

The invention comprises broadly adding to a kerosene, either a small or a large amount, depending upon the improvement desired, of a hydrogenated polymerized olefine product having the desired physical properties.

For example, hydrogenated tri-isobutylene has been found very satisfactory. This material may be made by polymerizing isobutylene with sulfuric acid to make a mixed polymerized product containing dimer, trimer and perhaps even higher polymers, separating the trimer by distillation and hydrogenating it. These processes will be described more in detail later on.

Instead of using isobutylene, other iso-olefines, 55

such as trimethyl ethylene and other isoamylenes,—hexylenes, etc., may be used; also, although the iso-olefines are preferred because they result in a final product having a low cloud point and low pour point, instead of using the pure iso-olefines, other hydrocarbon fractions preferably containing substantial amounts of iso-olefines may be used. For example, the fraction, known as C₄ cut, which is available in relatively large quantities in most refineries may be used advantageously. A typical composition of C₄ cut is as follows:

	Percent
Isobutylene	10.4
15 Total unsaturates (Isobutylene included)	32.4
Iso+normal butane	67.5
Pentane	0.1

If it is desired to use pure isobutylene, this may be prepared by known methods such as the thermolytic dehydration of tertiary butyl alcohol.

In carrying out the polymerization process, various methods may be used, but preferably the isobutylene or other olefines to be polymerized are contacted with sulfuric acid of various concentrations depending upon the temperature and time of contact used. One satisfactory method of operating is to concurrently disperse C₄ cut containing 10 to 15% isobutylene through 60% sulfuric acid by means of porous alundum thimbles in a suitable absorption vessel, using a super-atmospheric pressure of 40 pounds per square inch, and a temperature of 90° F., and using a feed rate of 20 parts per volume of C₄ cut per hour and three parts of acid per hour. The acid extract is then separated and polymerized at a suitable temperature which may be from 150° F. to 300° F. or more, depending upon the concentration of acid used and upon the time of heating. When using an extract prepared as described above in detail, the heating is preferably carried out at a temperature of about 200 to 225° F. with a heating time of 5 to 15 minutes or so. As illustrative of the variations which may be made in the process, the extraction may be carried out by contacting the C₄ cut with 65% sulfuric acid at 32° F. and the polymerization by heating the extract at 180° F.

Although sulfuric acid is the preferred polymerizing agent, other suitable catalytic liquids may be used, such as phosphoric acid or solutions of various salts such as zinc chloride or sulfates or phosphates of various metals, e. g., zinc, cadmium, etc., or polymerization catalysts of the active halide type such as aluminum chloride, boron fluoride, or the like may be used. In such cases the temperature may be even lower than indicated for the previous methods. For example, it may be as low as, or even lower than room temperature.

Although low temperature polymerization is preferred, it is possible to carry out the polymerization at elevated temperatures, such as 600 to 900° F. in the presence of solid catalysts, such as charcoal, clay, bauxite, etc. or at still higher temperatures, such as from 900 to 1000° F. at elevated pressures of 200 to 3,000 pounds or even 15,000 pounds per square inch or more.

After the polymerization has been completed, a product having the desired boiling range is separated by distillation or fractionation. One sample of the crude total polymer (made by polymerizing isobutylene with sulfuric acid) when subjected to fractionation gave the following results:

	Percent
Diisobutylene	35
Co-dimers*	10
Trimer	43
Higher polymers	5
Distillation loss (gas, etc.)	7

*Dimers produced by co-polymerization of isobutylene and alpha- or beta-butylene or some other constituent of C₄ cut, possibly butadiene or acetylenic compounds (some fractions with boiling points between those of di-isobutylene and tri-isobutylene have higher bromine numbers (e. g. 153, 181 and 167 as compared with 144 for di-isobutylene).

If the lighter 40% is distilled over from such a crude polymer, the residual 60% bottoms makes a satisfactory stock for feeding to the hydrogenation unit, according to the purview of the present invention. If desired, still narrower cuts of the polymers may be used. It is quite likely that in addition to obtaining a substantial proportion of triisobutylene in the above-described polymerization process, co-polymers are probably formed by reaction of the isobutylene or other iso-olefines with some of the straight chain olefines present.

The polymers, however they may have been formed, are then subjected to a saturation or hydrogenation in any desired manner, for example, by treatment with gaseous hydrogen under pressure, e. g. 200-5,000 pounds per square inch, preferably above 1,000, the partial pressure of hydrogen being usually about 70% of this total pressure. Relatively low temperature may be used for this purpose, for example, below 100 to 200° F., although it is preferable to use higher temperatures, e. g. 200 to 500° F.; and it is also desirable to use hydrogenation catalysts, e. g. nickel, cobalt, copper, platinum, palladium, manganese or copper chromite. Even higher temperatures may be used if desired, for example, above 600 or 700° F., especially where it is desired to obtain a limited destructive or carbon-chain-splitting action. For example, if the polymerization feed to the hydrogenation zone contains any substantial amount of tetramers, or higher boiling polymers, a considerable portion of these higher boiling fractions may be cracked during the hydrogenation to yield saturated polymers of lower molecular weight, particularly the trimers, together with some dimers which may or may not be removed by distillation. Catalysts for this latter type of hydrogenation are preferably immune to sulfur poisoning and may comprise the oxides, sulfides and nitrites of metals of the 6th group of the periodic table, e. g. molybdenum, chromium, tungsten or mixtures thereof with various other substances such as refractory oxides of the 2nd and 4th group, e. g. magnesium, zinc, titanium, etc., rare earths and the like.

The degree of hydrogenation may be varied accordingly to yield any quality desired. Generally the "smoke point" of the hydrogenated polymer increases directly with hydrogenation, and therefore, varies inversely with the bromine number, which of course, is gradually reduced during the hydrogenation. The progress of hydrogenation may be illustrated by the following table:—

Table III

	Bromine No.	"Smoke Point"
Polymer	100	22.5
Partially hydrogenated polymer	50	29
Completely hydrogenated polymer	2	Above 32

It has been found preferable to carry out the hydrogenation process with a gas rate of about 4,000 to 50,000, preferably 6,000 to 25,000 cu. ft. per barrel, and a low polymer feed rate (e. g. less than 3.0, and preferably even less than 1.0 or even as low as 0.3 volumes of feed per volume of catalyst per hour) when using a catalyst consisting of tungsten sulfide or molybdenum sulfide, although somewhat higher temperatures are used, e. g. up to 400 or 600° F. and super-atmospheric pressure. Such conditions give a yield of some 65 to 80% of hydrogenated product, boiling between the approximate limits of 300 and 425° F. and having an A. P. I. gravity between the approximate limits of 55.5 to 56.0; and a viscosity (Saybolt thermo) of 325-360.

The hydrogenated polymer, as it issues from the hydrogenation unit is distilled to remove any cracked products, and then may be used directly as such, or may be further finished by washing with a caustic soda solution to remove hydrogen sulfide.

When hydrogenated polymerized products other than relatively pure hydrogenated tri-isobutylene are used, these products should generally have approximately the following physical characteristics:—

Property	Approximate limits	Preferably
Molecular weight	125-225	150-160
Initial boiling point	275-325° F.	300-310° F.
Final boiling point	375-460° F.	400-425° F.
Flash point (Abel)	90-130° F.	100-125° F.
Bromine number	Less than 50	Less than 10
Pour point	Below -20° F.	Below -50° F.
Viscosity (Saybolt thermo)	300-400 secs.	350-375 secs.
A. P. I. gravity	45-60	50-55

As illustrative of the invention, the inspection of one sample of tri-isobutylene and of three samples of hydrogenated tri-isobutylene fractions produced in accordance with the above-described preferred methods, are given in the following table:

Table IV

Property	Tri-isobutylene	Hydrogenated tri-isobutylene		
		Sample A	Sample B	Sample C
A. P. I. gravity	53.4	52.8	55.8	55.8
Viscosity (Saybolt thermo)	345	346	330	330
Smoke point (calc.)		Above 32	Above 32	Above 32
Flash point (Abel -°F.)	112	100	105	115
Bromine number	100	43	2	1
Initial boiling point (°F.)	333	300	310	339
50% off (°F.)	346		350	350
Final boiling point (°F.)	356	420	400	364
Cloud point (°F.)		Below -20	Below -70	Below -70
Pour point (°F.)			Below -70	Below -70

The low cloud point and pour point of the hydrogenated polymers of the present invention constitute a distinct advantage over saturated hydrocarbons of the normal paraffin type, such as the following:

No. carbon atoms	N. paraffin	Mol. wt.	B. P. °F. 760 mm.	M. P. °F.
10	Decane	142	345	-26
11	Undecane	156	387	-16
12	Dodecane	170	421	10
13	Tridecane	184	453	21
14	Tetradecane	198	487	42
15	Pentadecane	212	519	50

It is apparent that although hydrogenated tri-isobutylene consists essentially of one or more

saturated hydrocarbons having 12 carbon atoms and therefore belongs to the class of "dodecanes", its cloud and pour points are much lower than those of the normal dodecane shown in the above list. It may also be noted that its boiling point, 5 333 to 356° F. (actually most of it boils between 343 and 348° F.) is considerably below 421° F., the boiling point of the normal dodecane.

The above described hydrogenated olefine polymers can be used alone as burning oils if 10 desired, but it is most economical to use them as blending agents for raising the smoke point of kerosene and other burning oil stocks which are 15 too low in quality to meet the desired specifications.

In such blending, the increase in paraffinicity as judged by the smoke point of the blend may be estimated from the following simple formula:

$$x = \frac{\text{S. P. of blend desired} - \text{S. P. of burning oil stocks}}{45 - \text{S. P. of burning oil stock}} \quad 20$$

Where S. P. = Smoke point.

For example, if the smoke point of the kerosene stock=23, and the smoke point desired in the blend=26 25

$$x = 100 \times \frac{26 - 23}{45 - 23} = 100 \times \frac{3}{22} = 14\% \quad 30$$

In other words, 14% of hydrogenated tri-isobutylene will raise the smoke point of a 23 S. P. kerosene up to 26. As another example, an 18 smoke point water-white kerosene stock can be improved to a 22 smoke point (Standard kerosene specification) by the addition of 15% hydrogenated trimer, both the kerosene stock and the hydrogenated trimer having a refined oil viscosity of 345. 35

As a further illustration of the invention, a blend was made using the hydrogenated tri-isobutylene sample "B", the properties of which were given in table IV, in an East Texas water-white kerosene stock with the following results: 40

45

Table V

	Straight East Texas water-white	Blend 17% hydro-tri-isobutylene 83% E. T. W. W.
A. P. I.	44.2	46.0
Viscosity	375	360
Abel (flash)	124	121
Smoke point	23	27

The A. S. T. M. Lamp Test (Report of Committee D-2 (1935); A. S. T. M. Designation: D 165-27) results as given below on the kerosenes from Table V further illustrated the marked improvement in properties of the kerosene blended with hydrogenated tri-isobutylene: 70 75

Table VI

A. S. T. M. lamp test	Straight East Texas water-white	Blend: 17% hydrogenated tri-iso-butylene 83% E. T. W. W.
(1) Consumption, ml/hour.	41.4	42.3
(2) Wick.	Not excessive crust.	Not excessive crust.
(3) Winkers.	None.	None.
(4) Smoke.	do.	Do.
(5) Flame hold.	6.0% decrease.	3.0% decrease.
(6) Flame cone.	Yellow streaks.	Blue.
(7) Flame color.	Similar to Mid-Continent kerosene.	Similar to high grade Pennsylvania kerosene.
(8) Flame shape.	Fair.	Excellent.
(9) Chimney.	do.	Do.

15 From the above table it is clear that the addition of 17% of hydrogenated tri-isobutylene to the kerosene base stock made a marked improvement in its properties for use as a burning oil, raising the smoke point from 23 to 27, and having substantially improved the flame and chimney characteristics.

20 It is not intended that the invention be limited to any of the specific examples given, nor any theories suggested as to the operation of the invention, but only by the appended claims, in which it is intended to claim all novelty inherent in the invention as broadly as the prior art permits.

25 I claim:—

30 1. As a new composition of matter, a kerosene containing approximately 5 to 50% of a hydro-

genated polymerized olefine having a molecular weight of approximately 125 to 225.

2. As a new composition of matter, a kerosene containing approximately 5 to 50% of a hydrogenated polymerized isobutylene having a molecular weight of approximately 125 to 225. 5

3. As a new composition of matter, a kerosene containing approximately 5 to 50% of a hydrogenated polymerized isobutylene having approximately the following properties. 10

Molecular weight 125-225
Boiling point range 275-450° F.
Viscosity (Saybolt thermo) 300-400 seconds
Bromine number Less than 50
Pour point Below -20° F. 15

4. As a new composition of matter, a kerosene containing approximately 5 to 50% of hydrogenated tri-isobutylene. 20

5. The method of improving kerosene for illuminating purposes which comprises adding thereto a hydrogenated polymerized olefine having a molecular weight of approximately 125 to 225, the product of such addition containing 5 to 50% of said hydrogenated olefine. 25

6. The method of improving kerosene for illuminating purposes which comprises adding thereto a hydrogenated polymerized isobutylene having a molecular weight of approximately 125 to 225, the product of such addition containing 5 to 50% of said hydrogenated isobutylene. 30

JOSHUA A. TILTON.
